CLAIM

The ornamental design for a tumbler lid, as shown and described.

DESCRIPTION

FIG. 1 is a top perspective view thereof in a closed configuration;

FIG. 2 is a bottom perspective view thereof in a closed configuration;

FIG. 3 is a front view thereof in a closed configuration;

FIG. 4 is a rear view thereof in a closed configuration;

FIG. 5 is a left side view thereof in a closed configuration;

FIG. 6 is a right side view thereof in a closed configuration;

FIG. 7 is a top view thereof in a closed configuration;

FIG. 8 is a bottom view thereof in a closed configuration;

FIG. 9 is a top perspective view thereof in an open configuration;

FIG. 10 is a bottom perspective view thereof in an open configuration;

FIG. 11 is a front view thereof in an open configuration;

FIG. 12 is a rear view thereof in an open configuration;

FIG. 13 is a left side view thereof in an open configuration;

FIG. 14 is a right side view thereof in an open configuration;

FIG. 15 is a top view thereof in an open configuration; and,

FIG. 16 is a bottom view thereof in an open configuration. The broken lines in the figures showing portions of the article form no part of the claimed design.
